UNITED STATES PATENT OFFICE.

THEODORE B. SMITH, OF AMSTERDAM, NEW YORK, ASSIGNOR TO HOUSE DRESS APRON CO., OF AMSTERDAM, NEW YORK, A FIRM.

DESIGN FOR AN APRON.

57,284.

Specification for Design.

Patented Mar. 8, 1921.

Application filed October 7, 1920. Serial No. 415,457. Term of patent 14 years.

To all whom it may concern:

Be it known that I, THEODORE B. SMITH, a citizen of the United States of America, residing at Amsterdam, in the county of Montgomery and State of New York, have invented a new, original, and ornamental Design for Aprons, of which the following is a specification, reference being had to the accompanying drawing, forming part thereof.

The single figure of the drawing is a front view of an apron, showing my new design.

I claim:

The ornamental design for an apron, as shown.

THEODORE B. SMITH.
